UNITED STATES PATENT OFFICE.

JOHN A. CHOPIESKA, OF PLATTS MOUTH, NEBRASKA.

PACKING-RING FOR INTERNAL-COMBUSTION ENGINES.

1,127,962.

Specification of Letters Patent.

Patented Feb. 9, 1915.

Application filed April 22, 1913. Serial No. 762,893.

To all whom it may concern:

Be it known that I, JOHN A. CHOPIESKA, a citizen of the United States, residing at Plattsouth, in the county of Cass and State of Nebraska, have invented a new and useful 5 Packing-Ring for Internal-Combustion Engines, of which the following is a specification.

The present invention relates to improvements in packing rings for internal combustion engines, one object of the present invention, being the provision of a packing ring which is provided with the necessary resiliency and yet at the same time has no 10 peripheral interstices that permit of the passage of the gasses exteriorly of the piston, thus causing the maximum power to be exerted upon the piston and also permitting the highest compression of the explosive 15 charge within the cylinder.

A further object of the present invention is the provision of a sectional packing ring, in which all of the various meeting edges of the sections are so protected and disposed as 20 to prevent a direct passageway or channel for the gases due to the compression or explosive stroke, thus providing a tight resilient joint at all times between the piston and cylinder and guaranteeing the maximum 25 pressure while the gas is being compressed, and a maximum power stroke due to explosion of the charge.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

In the drawings—Figure 1 is a sectional view through a portion of a cylinder of an 40 internal combustion engine, and its piston with the present packing ring applied. Fig. 45 2 is a top plan view of the complete ring. Fig. 3 is a side elevation thereof. Fig. 4 is a section taken in line 4—4 of Fig. 2. Fig. 5 50 is a view illustrating a method of permanently connecting the sections of the ring.

Referring to the drawings, the numeral 1 designates the cylinder of an explosive 55 engine, and 2 the piston, which is provided with the present packing ring 3, a detail structure of which will be set forth later on.

In internal combustion engines it has been found desirable in order to secure the maximum power from the minimum mixture, to employ a packing ring, which has the necessary resiliency and yet at the same time has no peripheral interstices that permit of the passage of the gases exteriorly of the piston, thus causing the maximum power to be exerted upon the piston during the explosive stroke and also permitting the highest compression of the explosive charge within the cylinder. The present packing ring has therefore been designed to have these features, and consists of the internal 60 outwardly expanding ring 4, the same being the innermost member of the packing ring as shown in Fig. 4.

The present ring, consists of the internal outwardly expanding member or ring 4, 75 which is the innermost member of the present ring. Disposed about the ring 4 is the sectional metallic ring 5, each section 6 of which is provided with the oblique ends 7, so that when the ring is assembled to provide a circumferential groove 8 for the reception of the sectional ring 9, the sections 10 of which are constructed similarly to the sections 6 of the ring 5, the joints however being placed to alternate with the joints of 80 the ring 5, as clearly shown in Fig. 3. By this means, the wear upon the outer surface of the sectional rings 5 and 9, is equalized and as the rings are formed of four or more sections, the same are permitted to be so 85 expanded by the spring ring 4, as to conform exactly to the walls of the cylinder 1 and thus produce a tight resilient packing between the piston and cylinder which will not have peripheral interstices and which 90 will be so tight as to prevent the passage of the explosive charge beyond the ring during the compression stroke or the exploded gases beyond such packing ring upon the explosive stroke.

A pin 11 is carried by one section 6 and is disposed as shown in Fig. 3 to project between the oblique ends of two adjacent sections 10 of the ring 9, and locks the sections of the entire ring against collapsing and 100 also holds the sections of both rings 5 and 9 in fixed circumferential relation.

As shown in Fig. 5, two rivets 11' are positioned to permanently connect one section of the ring 6 to one section of the ring 9, thus providing a "keystone" locking means for locking the sections when nested,

and also provides a better joint than at pin 11 in Fig. 3. In the use of pin 11, should the same wear loose, a port for the escape of compression may result, but when the rivets 11' are employed this is eliminated.

What is claimed is:

1. The combination with the cylinder of an explosion engine, and a power piston provided with a plurality of circumferential packing ring recesses, of a packing ring for each recess, including a main annulus having a portion of its periphery recessed the full circumference thereof, said main annulus being composed of a plurality of segments, the meeting faces of which are angularly disposed relative to the flat faces of the annulus, a second annulus fitting in the recessed periphery of the main annulus with its body wholly within the area thereof, the second annulus being composed of a plurality of sections, the meeting faces of which are angularly disposed relatively to the flat faces of the second annulus and substantially at right angles to the meeting faces of the sections of the main annulus, the sections of the main annulus, the meeting faces of one annulus being out of alignment with those of the other, means for securing one section of each annulus rigidly together, and a single open expanding ring nested within the main annulus to hold the sections outwardly and resiliently in con-

tact with the inner face of the cylinder of the engine.

2. A packing ring, comprising a main annulus having a portion of its periphery recessed the full circumferential area thereof, said main annulus being composed of a plurality of segments, the meeting faces of which are angularly disposed relatively to the flat faces of the annulus, a second annulus fitting in the recessed periphery of the main annulus with its body wholly therewithin, the second annulus being composed of a plurality of sections, the meeting faces of which are angularly disposed relatively to the flat faces of the second annulus and substantially at right angles to the meeting faces of the sections of the main annulus, the meeting faces of one annulus being out of alignment with those of the other, means for piercing one section of each annulus for rigidly connecting such sections together, a single open expanding ring nested within the main annulus and fitting the inner circumference thereof.

In testimony that I claim the foregoing as my own, I have hereto affixed my signature in the presence of two witnesses.

JOHN A. CHOPIESKA.
